COMBINED CARRYING AND STORAGE CASE

Peter T. Schurman, Woodbridge, Conn., assignor to The Plastic Forming Company, Inc., Woodbridge, Conn.

Filed July 1, 1968, Ser. No. 12,586

Term of patent 14 years

Int. Cl. D3—99

U.S. Cl. D87—1

Fig. 1.

Fig. 2.

Fig. 3.

Fig. 4.

Fig. 5.

FIG. 1 is a top plan view of a combined carrying and storage case showing my new design;

FIG. 2 is a front elevational view thereof;

FIG. 3 is an end elevational view thereof;

FIG. 4 is a bottom plan view thereof; and

FIG. 5 is a rear elevational view thereof.

The end not shown in FIG. 3 is a mirror image of the end shown therein.

I claim:

The ornamental design for a combined carrying and storage case, substantially as shown and described.
